UNITED STATES PATENT OFFICE.

DONALD T. ALLEN, OF MILWAUKEE, WISCONSIN, ASSIGNOR TO PRIME MFG. CO., OF MILWAUKEE, WISCONSIN.

PHONOGRAPH-CASE CONSTRUCTION.

Application filed August 29, 1925. Serial No. 53,354.

To all whom it may concern:

Be it known that I, DONALD T. ALLEN, a citizen of the United States, and resident of Milwaukee, in the county of Milwaukee, 5 and State of Wisconsin, have invented certain new and useful Improvements in Phonograph-Case Constructions; and I do hereby declare that the following is a full, clear, and exact description thereof.

10 This invention relates to phonograph case construction.

In certain types of phonographs, such as the portable ones, it has been the practise to provide a sound box below the tone arm and connecting such tone arm with the main outlet. This sound box has universally been made of metal and has been of rounded construction to facilitate the forming operations. The metal has not been satisfactory 20 due to the tiny sounds and also the curved shape has been found to distort the sounds materially.

Further, this construction has been found to be relatively expensive and materially 25 adds to the cost of the instrument.

This invention is designed to overcome the above noted defects, and objects of this invention are to provide a sound box which is non-metallic, which is of angular construction, and which is so made that it is possible to employ a large amount of scrap material in its manufacture, and to thus materially reduce the cost of this portion of the device.

35 An embodiment of the invention is shown in the accompanying drawings, in which:—

Figure 1 is a fragmentary sectional view through the sound box.

Figure 2 is a bottom view thereof.

40 Figure 3 is a side elevation.

Referring to the drawings, it will be seen that the usual tone arm is indicated at 1, and that the top 2 is provided with the usual outlet 3. The sound box is constructed 45 primarily of three members of fiber board. A pair of side members, indicated by the reference character 4, are provided and have flat upper edges, as shown in Figures 1 and 3. Their lower sides are defined by an angular edge 5 which joins a second downwardly extending angular edge 6.

From the lowest point of the edge 6 a second edge 7 extends upwardly to the forward portion of the box, as most clearly 50 brought out in Figure 3.

The bottom of the box consists of a fiber strip which is flared from one end to the other, and is scored and folded so as to provide a flat face 8 conforming to the edge 5, a second flat face 9 conforming to the edge 6 and a third flat face 10 conforming to the edge 7. The score lines are positioned at the corners where the fold occurs to facilitate this operation. The side edges have pasted thereto the glued fabric strips 11 65 which extend completely across and beyond such side portions. Their ends are folded in, as indicated at 12 and 13, in Figure 2, across the faces 8 and 10 of the bottom of the box. These fabric strips have outwardly projecting flaps 14 for a purpose hereinafter to appear. End strips 15 and 16 are glued to the faces 8 and 10 and also are glued down upon the folded ends 12 and 13 of the strips 11, as shown most 70 clearly in Figure 2. These end strips are provided with free outwardly turned portions 17 and 18.

The box is lined by means of the covering or strip 19 (see Figure 1) which terminates at the edges of the box, as shown. This strip may continue up the inner sides of the box, and may be one blank or may be composed of a plurality of blanks. If desired, the bottom of the box may also be glued to 80 the side portions 4. However, it is to be noted that the inturned ends 12 and 13 of the strips 11 tie the bottom to the side edges in a very secure manner, and such tying ends are held down also by means of the glued 85 strips 15 and 16.

After the sound box has been formed the edges thereof are coated with glue, together with the projecting flaps 14, 17, and 18, such flaps and edges are stuck to the under side 90 of the top 2, as shown in Figure 1, thus securely attaching the sound box in position, so as to connect the tone arm with the outlet 3.

It is to be noted that the flat bottom face 100 8 deflects the sound towards the flat face 10 without interference and such sound is projected upwardly through the outlet 3. Further, any angularly directed sound waves will strike the slanting surface 9 and will 105 also be reflected and projected out of the opening 3. It has been found that this angular construction does not produce a throaty or imperfect articulation but produces a remarkably clear articulation. 110

It is to be particularly noted that the material forming this sound box is extremely cheap and is non-metallic. Further, it is the usual practise to form the tops and sides 5 of these phonographs with a finishing covering 20 (see Figure 1) of fabric or imitation leather.

In practising this invention, the scraps 10 of this material are employed in forming the sound box and are used for the strips, whereby the parts are attached together, as described above. This also materially reduces the cost of construction.

Further, it is to be particularly noted that 15 the sound boxes may be readily constructed and set aside until dried, and thereafter, may be most easily attached in their correct position to the under side of the top, thus materially aiding in the process of manufacture.

Although the invention has been described 20 in considerable detail, it is to be understood that the invention may be variously embodied and is, therefore, to be limited only as claimed.

I claim:

1. A sound box for phonographs comprising a pair of side faces having angular bottom edges, a bottom secured to the edges of

the sides, said bottom and sides being formed 30 of non-metallic material, and glued flexible strips secured to said bottom and sides and having projecting attaching flaps.

2. In a phonograph, the combination of a top, a sound arm opening downwardly therethrough, said top having a delivery opening, a sound box positioned below said top, and connecting said tone arm and said delivery opening, said sound box having a pair of flat sides provided with angular bottom 40 edges, a bottom secured to said angular bottom edges and sharply bent at the ends of each of said edges, fabric strips glued to said sides and having inwardly turned projecting ends overlapping said bottom, end strips 45 glued to said bottom and overlapping the said inwardly turned ends, each of said strips having outwardly projecting flaps glued to the under side of the said top, said sound box having one of the angular faces 50 of its bottom positioned directly below said tone arm.

In testimony that I claim the foregoing I have hereunto set my hand at Milwaukee, in the county of Milwaukee and State of 55 Wisconsin.

DONALD T. ALLEN.
